(57) **CLAIM**

The ornamental design for a valve bridge, as shown and described.

DESCRIPTION

FIG. 1 is a perspective view of a valve bridge showing the new design.

FIG. 2 is a first side view of the valve bridge of FIG. 1.

FIG. 3 is a second side view of the valve bridge of FIG. 1.

FIG. 4 is a top view of the valve bridge of FIG. 1.

FIG. 5 is a bottom view of the valve bridge of FIG. 1.

FIG. 6 is a front view of the valve bridge of FIG. 1.

FIG. 7 is a rear view of the valve bridge of FIG. 1.

FIG. 8 is a perspective view of a second embodiment of a valve bridge showing the new design.

FIG. 9 is a first side view of the second embodiment of the valve bridge of FIG. 8.

FIG. 10 is a second side view of the second embodiment of the valve bridge of FIG. 8.

FIG. 11 is a top view of the second embodiment of the valve bridge of FIG. 8.

FIG. 12 is a bottom view of the second embodiment of the valve bridge of FIG. 8.

FIG. 13 is a front view of the second embodiment of the valve bridge of FIG. 8.

FIG. 14 is a rear view of the second embodiment of the valve bridge of FIG. 8.

FIG. 15 is a perspective view of a third embodiment of a valve bridge showing the new design.

FIG. 16 is a first side view of the third embodiment of the valve bridge of FIG. 15.

FIG. 17 is a second side view of the third embodiment of the valve bridge of FIG. 15.

FIG. 18 is a top view of the third embodiment of the valve bridge of FIG. 15.

FIG. 19 is a bottom view of the third embodiment of the valve bridge of FIG. 15.

FIG. 20 is a front view of the third embodiment of the valve bridge of FIG. 15; and,

FIG. 21 is a rear view of the third embodiment of the valve bridge of FIG. 15.

The accompanying drawings also form a part of the specification. Any portion of the valve bridge shown in broken lines is for the purpose of illustrating environmental structure and forms no part of the claimed design.

1 Claim, 9 Drawing Sheets
